SEPARABLE FASTENER

Sena M. Ward, New York, N. Y.

Application March 13, 1936, Serial No. 68,784

5 Claims. (Cl. 24—226)

My present invention relates to improvements in separable fasteners particularly adapted for detachably connecting garments such as corsets or girdles, and garters.

5 In my prior Patent 1,896,129 and in my co-pending application, Serial Number 755,982, filed December 4, 1934, I have disclosed separable fasteners somewhat similar to the fastener forming the subject matter of my present application, but differentiating in material respects hereinafter pointed out.

The principal general object of the present invention is the same as that set forth in my said patent and co-pending application, namely, 15 the provision of a separable fastener of relatively thin nature composed of two parts, one adapted, for instance, for attachment to a girdle or corset, and the other adapted for connection with a garter, and each part having cooperating or interchangeable elements to detachably connect the parts and hold the girdle or corset and garter in fastened relation on the body of the wearer without creating on garments worn thereabove any noticeable bulge or irregular surface.

20 In my said co-pending application, I have disclosed a separable fastener comprising two flat or thin members, one foldable upon itself to provide in cross-section a substantially U-shaped thin part provided with a narrow elongated opening extending through the crown of the fold and having located thereabove lateral extensions in one of the arms through which lateral extensions on the other member may be inserted when the parts are assembled to detachably connect the two members. The fastener constructed in accordance with the disclosure of my said application is efficient to the accomplishment of the general objects of the invention, but I have found that I may 25 reduce the size of the fasteners while accomplishing the desired results and also facilitating the attachment and detachment of the parts of the fastener.

In the light of the foregoing, the general 45 principal object of the invention may be stated to reside in the provision of a separable fastener of the character described which will safely maintain the parts of the garment in connected relation, and which greatly facilitates the detachment of the parts of the garment due principally to the facility of manipulating the parts of the fastener during their relative approaching or attaching movements as well as their separating or detaching movements.

50 All of the objects and advantages of the in-

vention will be pointed out and will become more apparent during the course of the following detailed description of the accompanying drawing, in which

Fig. 1 is a front view in elevation of a separable fastener constructed in accordance with the present invention and showing the parts of the fasteners secured to fragments of garments; 5

Fig. 2 is a sectional view taken on the line 2—2 of Fig. 1;

Fig. 3 is an exploded perspective view of the 10 fastener shown in Fig. 1;

Fig. 4 is a view similar to Fig. 1 showing a modification of the invention;

Fig. 5 is a longitudinal sectional view showing 15 the parts of the fastener at their intermediate point of attachment or detachment; and

Fig. 6 is a sectional view taken on the line 6—6 of Fig. 4.

Referring first to Fig. 3 of the drawing, "A" 20 designates generally one part of the fastener, and "B" designates generally the other part of the fastener. The part "A" may be referred to as the kept part which may be attached to the upper garment, and "B" designates what may be termed as the keeper attached to the lower garment or garter as shown in Fig. 1 as presently described.

The part "A" is formed of any suitable material, preferably thin metal, and is provided at 30 its top with a slot 7 formed through the elongated head 6, so that (as shown in Fig. 1) stitches 8 may be sewn through the upper garment "C" and through the slot 7 to attach the part "A" to the garment "C" which may be the corset or the girdle. Depending from the head 6 of the member "A" is a tongue 9 preferably of less width than the head 6 and provided centrally with an opening 10 adjacent the lower end of the head 6, that is, below the slot 7. 35 It should be understood that the member "A" may be stamped, molded, or otherwise formed from a single piece of metal or other suitable material and is preferably of very thin nature, although the drawing greatly exaggerates the 40 actual size and thickness.

The other member of the fastener, that is, the keeper, comprises a sheet of metal of similar material folded or bent upon itself to form a wall 11 provided with openings 12 to receive 50 (see Fig. 1) stitches or other fastening elements 13 to attach the keeper to the other garment or garter "G", and a wall 14 of less length than the wall 11. Preferably the part "B" is stamped from a sheet of metal or other suitable 55

material, or is so molded or fabricated as to provide in cross-section a relatively thin substantially U-shaped structure, and a portion of the wall 14 is removed or eliminated to provide an opening 15 into which extends a tongue 16 bent over from a portion of the wall 11. I would further point out that the relative widths of the tongue 9 and the opening 15 is substantially the same but such as to permit sliding movement of the tongue 9 through the opening 15. Furthermore, the length of the tongue 9 is greater than the length of the opening 15 so that the lower end of the tongue 9 will be disposed under the lower end 17 of the arm 14 when inserted in the opening 15, which insertion is accomplished as shown in Fig. 5 by inclining the member "A" relative to the member "B". I also deem it important to have the opening 10 on the tongue 9 so related relative to the location and dimension of the tongue 16 on the part "B" as to bring the opening 10 into substantial registry with the tongue 16 at or about the time the lower end of the head 6 on part "A" substantially alines with the fold 19 connecting arms 11 and 14. The opening 10 is positioned to receive the tongue 16 when the parts "A" and "B" are brought into straightened position, that is, into substantially the same plane, so that the fold 20 on tongue 16 will engage the edge 21 of the opening 10 and with the end of the tongue 9 disposed under the lower end 17 of arm 14 to hold the parts against accidental separation.

The manner of disconnecting the parts is just the reverse of the manner of attaching the parts, that is, the parts "A" and "B" are brought into approaching relation until the opening 10 is in registry with the tongue 16, so that the parts may be relatively inclined to permit withdrawal of the tongue 9 from under the portion 17 of part "B".

In Figs. 4-6 the primed numerals indicate the same parts as described in connection with the unprimed numerals of Figs. 1-3. The only difference is that a portion of the part 17' or member "B" at the lower end of the opening 15' is slightly curved upwardly as indicated by the numeral 21 to facilitate insertion of the tongue 9 between the arms 14 and 11. This is shown quite clearly in Fig. 5.

It should be apparent from the foregoing, that very thin, unnoticeable, quickly attachable and detachable separable fasteners may be provided at a minimum of expense, and of such nature as to assure the wearer that the garments will not become accidentally separated unless one of the garments should become broken.

What I claim is:

1. A separable fastener for connecting adjoining garments comprising a relatively thin and flat keeper or retaining member comprising a substantially U-shaped part in cross section, one of the arms of said member having a portion removed to provide an opening therein extending from the crown of the fold toward the free end of said arm, a projection on the other arm located in said opening, a retained or kept part comprising a relatively thin plate having a portion to slidably fit within said opening of the retaining member or keeper when said retained member is inclined relative to said retaining member and having an opening to register with and receive said projection when the parts are brought into substantial parallelism.

2. A separable fastener for connecting adjoining garments comprising a relatively thin and

flat keeper or retaining member composed of a sheet folded upon itself to provide a substantially U-shaped part in cross section, one of the arms of said member having a portion removed to provide an opening therein extending from the crown of the fold toward the free end of said arm, a projection on the other arm located in said opening, a retained or kept part comprising a relatively thin plate having a portion to slidably fit within said opening of the retaining member or keeper when said retained member is inclined relative to said retaining member or keeper, and said portion of the retained or kept member having an opening to register with and receive said projection when the parts are brought into substantial parallelism.

3. A separable fastener for connecting the confronting ends of undergarments comprising, a relatively thin and flat keeper or retaining member composed of a sheet folded upon itself to provide a substantially U-shaped part in cross section, one of the arms of said member having a substantially central portion removed to provide an opening extending from the crown of the fold toward the free end of said arm, a projection on the other arm of said member located in said opening, a retained or kept part comprising a relatively thin plate having a portion to slidably fit within said opening of the retaining member or keeper when said retained member is inclined relative to said retaining member or keeper, said portion of the retained or kept member having an opening to register with and receive said projection when the parts are brought into substantial parallelism, the portion of said retained member which fits within said opening of the retaining member being of greater length than the length of said opening, whereby the free end of said portion is disposed beneath said first arm when the parts are connected by interengagement of said projection and opening in the retained member to afford stability to the fastener.

4. A separable fastener for connecting undergarments comprising, a relatively thin and flat keeper or retaining member composed of a sheet folded upon itself to provide a substantially U-shaped part in cross section, one of the arms of said member having a portion removed to provide an opening extending from the crown of the fold toward the free end of said arm, a projection on the other arm of said member in alinement with the crown of the fold and bent over within said opening with its free end extending toward the free end of said one arm, a retained or kept part comprising a relatively thin plate having a portion to slidably fit within said opening of the retaining member or keeper when said retained member is inclined relative to said retaining member or keeper, and said portion of the retained or kept member having an opening to register with and receive said projection when the parts are brought into substantial parallelism.

5. A separable fastener for connecting undergarments comprising, a relatively thin and flat keeper or retaining member composed of a sheet folded upon itself to provide a substantially U-shaped part in cross-section, one of the arms of said member having a portion removed to provide an opening therein extending from the crown of the fold toward the free end of said arm, a projection on the other arm in alinement with the crown of the fold and bent over within said opening with its free end extending toward

the end of said one arm, a retained or kept part comprising a relatively thin plate having a portion to slidably fit within said opening of the retaining member or keeper when said retained member is inclined relative to said retaining member or keeper, and said portion of the retained or kept member having an opening to register with and receive said projection when the parts are brought into substantial paral-

lelism, the portion of said retained member which fits within said opening of the retained member being of greater length than said opening whereby the free end of said portion is disposed beneath the end of said first arm when the parts are connected to afford stability to the fastener. 5
